Specification for Design.

Patented Aug. 24, 1915.

Application filed May 10, 1915. Serial No. 27,271. Term of patent 7 years.

To all whom it may concern:

Be it known that I, JOSEPH P. GADLE, Jr., a citizen of the United States, residing at Norwich, in the county of New London and State of Connecticut, have invented a new, original, and ornamental Design for a Combined Water-Glass and Cream-Glass Holder, of which the following is a specification, reference being had to the accompanying drawing, forming part thereof.

The figure is a perspective view of a combined water-glass and cream glass-holder, showing my new design.

I claim:

The ornamental design for a combined water glass and cream glass holder, as shown.

JOSEPH P. GADLE, JR.
